CLAIM

The ornamental design for a label sheet assembly, as shown and described.

DESCRIPTION

FIG. 1 is a perspective view of a first embodiment of a label sheet assembly showing my new design;

FIG. 2 is a front view of FIG. 1 thereof;

FIG. 3 is a back view of FIG. 1 thereof;

FIG. 4 is a first side view of FIG. 1 thereof;

FIG. 5 is a second side view of FIG. 1 thereof;

FIG. 6 is a top view of FIG. 1 thereof;

FIG. 7 is a bottom view of FIG. 1 thereof;

FIG. 8 is a perspective view of a second embodiment of a label sheet assembly showing my new design;

FIG. 9 is a front view of FIG. 8 thereof;

FIG. 10 is a back view of FIG. 8 thereof;

FIG. 11 is a first side view of FIG. 8 thereof;

FIG. 12 is a second side view of FIG. 8 thereof;

FIG. 13 is a top view of FIG. 8 thereof;

FIG. 14 is a bottom view of FIG. 8 thereof;

FIG. 15 is a perspective view of a third embodiment of a label sheet assembly showing my new design;

FIG. 16 is a front view of FIG. 15 thereof;

FIG. 17 is a back view of FIG. 15 thereof;

FIG. 18 is a first side view of FIG. 15 thereof;
